FOUNTAIN

Alfred W. Kaufmann, Brooklyn, N. Y.

Application November 4, 1957, Serial No. 48,324

Term of patent 7 years

(Cl. D91—4)

The figure is a perspective view of a fountain, showing my new design.

The side view of the fountain not shown is substantially the same in appearance as the side shown.

The dominant features of my design reside in the portions shown in full lines.

I claim:

The ornamental design for a fountain, as shown and described.
